ELECTRICAL CONNECTOR

August G. Luisada, Carbondale, Pa., assignor to Leonard P. Frieder, Great Neck, N. Y.

Application November 17, 1955, Serial No. 547,524

8 Claims. (Cl. 339—107)

This invention relates to electrical connectors, and particularly to connectors of the plug and jack type, which may be subject to severe strains in the attached wires, which strains may result in the wear or fraying of the insulation of the wire or in pulling the wire loose from the connector plug.

The present connector was particularly designed for use in connecting earphones attached to a safety helmet to associated electrical equipment carried on the body of the person using that equipment.

A connector of the type described includes a flexible wire comprising one or more insulated conductors connected to a plug of rigid insulating material which is attached more or less rigidly to a similarly rigid jack. The conductors are connected electrically to contacts in the plug or jack. The stresses transmitted through the wire to the plug may be classified as either tension stresses due to pulling of the wire, or torsional stresses due to twisting of the wire. It is desired to have the stresses which pass along the wire transmitted through the insulation of the wire to the plug, so that the electrical connection will not be disturbed by those stresses.

An object of the present invention is to provide an improved electrical connector of the type described.

Another object is to provide an electrical connector of the type described including improved means for transmitting tensional and torsional forces through the insulating covering of the wire to an insulating plug.

Other objects and advantages of the invention will become apparent from a consideration of the following description and claims, taken together with the accompanying drawing.

In the drawing:

Fig. 1 is a plan view of an electrical connector embodying the invention;

Fig. 2 is a front elevational view of the connector of Fig. 1;

Fig. 3 is a sectional view taken on the line III—III of Fig. 2, with certain parts broken away;

Fig. 4 is a sectional view taken on the line IV—IV of Fig. 1;

Fig. 5 is a sectional view taken on the line V—V of Fig. 4; and

Fig. 6 is a sectional view taken on the line VI—VI of Fig. 4.

There is shown in the drawing, a wire generally indicated at 1, connected to a plug 2. The plug 2 is longitudinally split into upper and lower sections 3 and 4 which are held together by bolts 5 and nuts 6. The two sections 3 and 4 of the plug have opposed facing recesses 3c, 4c, for receiving the end of the wire and other internal parts of the connector. The wire is illustrated as having two internal conductors 7, although it should be readily understood that the number of conductors is immaterial and that the invention is applicable to a cable of one or more conductors. The conductors are encircled by a braided sleeve 8 of tough flexible material,

2

such as heavy cotton. A covering 9 of molded plastic material encircles the sleeve 8. The covering or sheath 9 includes a gradually tapered portion extending outwardly from the plug for a substantial distance, and decreasing in thickness in a direction away from the plug, until it finally reaches the thickness illustrated at 10 in Fig. 3.

The sheath 9 terminates short of the ends of the wires 7. Adjacent its end, the sheath 9 is provided with a circular flange 10, a portion 11 of a generally elliptical cross-section, another flange 12, circular like the flange 10 but substantially thicker, and finally a portion 13 of rectangular cross-section. The plug sections 3 and 4 have their central recesses 3b, 4b, formed to correspond to the shape of the portions 10, 11, 12 and 13 of the sheath, the various parts of the sheath fitting closely within the plug sections. The conductors 7 have slack end portions 7a attached, as by soldering, to leaf spring conductors 14. The conductors 14, and backing leaf springs 16, are attached, as by rivets 17 to squared bases formed on the inner ends of hollow cylindrical sockets 15, adapted to receive pins on a cooperating plug. The free ends of the conductors 14 extend through openings 15a in the sides of the sockets 15, so as to engage frictionally pins which may be received therein.

Any tension stress applied to the wire 1 is transmitted to the plug 2 through the flange 10. Since the flange 10 is relatively thin, it may deform in the presence of such stresses, in which case part of the stress is taken up and transmitted to the plug by the heavier flange 12. Light torsional stresses are absorbed by the elliptical section 10 of the sheath and transmitted thereby to the plug. The section 11 is capable of some deformation under such stresses. The stresses are further absorbed and transmitted to the plug by the rectangular sheath section 13, which is effective to absorb even greater stresses.

It may be seen that the structure shown and described is capable of transmitting torsional and tensional stresses of substantial magnitude between the wire 1 and the plug 2, without transmitting those stresses through the ends 7a of the conductors 7 and the other electrically conductive parts.

The plugs 3 and 4 have central portions 3a and 4a, best seen in Fig. 5, which are offset from the plane of their edge portions 3b and 4b. The central recesses which receive the flanged and noncircular portions of the sheath 9 are located in these offset portions 3a and 4a. By providing this offset arrangement, the center line of the wire and of the plug may be offset laterally from the center line of the connector end.

While I have shown and described a preferred embodiment of my invention, other modifications thereof will readily occur to those skilled in the art, and I therefore intend my invention to be limited only by the appended claims.

I claim:

1. An electrical connector comprising at least one flexible conductor, a sheath for said conductor of yieldable, resilient insulating material terminating at a point adjacent but spaced from an end of the conductor, a hollow plug of rigid insulating material receiving said end of said conductor and the adjacent end of the sheath, contact means in said plug, means conductively connecting the end of the conductor to the contact means, and means for relieving torsional stresses in said conductor and preventing said stresses from reaching said connecting means, said torsional stress relieving means comprising a portion of said sheath of substantially elliptical cross section and means in said plug defining a cooperating substantially elliptical recess for receiving said substantially elliptical sheath portion.

2. An electrical connector as defined in claim 1, including means for relieving tension stresses in said conductor and preventing said tension stresses from reaching said connecting means, said tension stress relieving means comprising an annular flange on said sheath and spaced lengthwise thereof from said torsional stress relieving means, and means in said plug defining a recess for receiving said flange.

3. An electrical connector, as defined in claim 1, in which said sheath comprises a braided sleeve encircling the conductor, and a layer of molded plastic insulating material encircling the sleeve, said sheath portion being molded in said layer.

4. An electrical connector comprising at least one conductor, a sheath for said conductor of yieldable, resilient insulating material terminating at a point adjacent but spaced from the end of the conductor, a hollow plug of rigid insulating material receiving said end of said conductor and the adjacent end of the sheath, contact means in said plug, means conductively connecting the end of the conductor to the contact means, and means for relieving torsional and tensional stresses in said conductor and preventing said stresses from reaching said connecting means, said strain relieving means comprising four adjacent portions extending along said sheath from the end thereof, the portion nearest the end being of rectangular cross-section, the second portion from the end being somewhat longer and of circular cross-section, the third portion from the end being of substantially elliptical cross-section and shorter than said second portion, the fourth portion from the end being of circular cross-section, said second and fourth portions being of substantially greater diameter than the rest of the sheath, and means in said plug defining a conforming recess for receiving said four sheath portions.

5. An electrical connector as defined in claim 4, in which said sheath comprises a braided sleeve encircling the conductor, and a layer of molded plastic insulating material encircling the sleeve, said four sheath portions being molded in said layer, said layer also comprising a tapered portion extending along the conductor a substantial distance from said four portions and decreasing in thickness in the direction away from said end.

6. An electrical connector as defined in claim 5, in which said plug comprises two longitudinally separated halves, said halves having central abutting plane portions offset laterally from the adjacent edge portions, said

recess defining means being located in said abutting plane portions.

7. An electrical connector as defined in claim 1, in which said torsional stress relieving means comprises a further portion of said sheath of rectangular cross-section spaced lengthwise of the sheath and toward the end thereof from said portion of substantially elliptical cross-section, and means in said plug defining a conforming recess for receiving said portion of rectangular cross-section, said elliptical portion of the sheath being effective to transfer from the conductor to the plug torsional stresses of less than a predetermined value sufficient to deform said elliptical portion, and said rectangular portion of the sheath being effective to transfer torsional stresses to the plug from the sheath after said elliptical portion has been deformed.

8. An electrical connector comprising at least one flexible conductor, a sheath for said conductor of yieldable, resilient insulating material terminating at a point adjacent but spaced from an end of the conductor, a hollow plug of rigid insulating material receiving said end of said conductor and the adjacent end of the sheath, contact means in said plug, means conductively connecting the end of the conductor to the contact means, and means for relieving tension stresses in said conductor and preventing said tension stresses from reaching said connecting means, said tension stress relieving means comprising two flanges, encircling said sheath and spaced lengthwise thereof, the flange nearest the end of the sheath being substantially thicker than the other flange, and means in said plug defining recesses for receiving said flanges, said other flange being effective to transfer from the conductor to the plug tensile stresses of less than a predetermined value sufficient to deform said other flange, and said flange nearest the end of the sheath being effective to transfer tensile stresses to the plug from the sheath after said one flange has been deformed.
